UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,120.

Specification of Letters Patent.

Patented Aug. 9, 1921.

Application filed January 16, 1920. Serial No. 351,791.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings representing like parts.

This invention pertains to improvements in separable fasteners, and more particularly, though not exclusively, to fasteners, in which a lateral lock is provided against separation of stud and socket by lateral strain, this being effected by permitting rotation or partial rotation of the socket to bring the same when under lateral strain into the most favorable position to resist such strain.

In the drawings, which show a preferred form of one embodiment of my invention:

Figure 1 is an elevation of two pieces of fabric secured together by a preferred form 25 of fastener;

Fig. 2 is a section on the line 2—2 of Fig. 1;

Fig. 3 is a section on the line 3—3 of Fig. 2; and

Fig. 4 shows a modification of my invention, being a section on the same plane as Fig. 2.

It is well known that certain types of fastener tend more satisfactorily to resist separation of stud and socket under some lateral strains than under other lateral strains. Separation under lateral strain takes place particularly easily in the ordinary fastener where the strain is exactly or substantially 40 in a direction perpendicular to the spring jaws.

I have elected to disclose as a preferred embodiment of the present invention, a fastener in which separation of stud and socket under lateral strain is opposed by notches in the stud-receiving aperture of the socket, these operating on the general principle shown in my copending application, Serial No. 307,111, filed June 27, 1919. The invention is of use, however, in connection with other types of socket.

Referring to the drawings, I have shown a stud 5 of usual construction, coöperating

with a socket casing 6 of the type shown in copending application above referred to, the 55 socket casing being secured to the socket-carrying fabric 7 by securing means permitting rotation of the socket casing 6 after attachment thereof to the fabric 7. I may provide for this rotation in any suitable way, 60 but I preferably do so by securing the socket casing to the fabric as shown in Fig. 2 by means of a socket-containing part 8, which may be secured to the fabric 7 in any suitable way, herein shown as including a 65 rivet 9 and a washer 10. It will be understood that the socket-containing part 8 loosely surrounds the socket casing 6 so that the latter may turn. One of the other various satisfactory ways of practising my invention is shown in Fig. 4, wherein the socket casing 6 is secured to the socket-carrying fabric 7 by a socket-carrying plate 11 which performs the same functions as the socket-containing part 8 shown in Fig. 2, but is constructed in a somewhat different way, being adapted to engage beneath the flange 12 of the socket casing 6. The socket-carrying plate 11 may be secured to the fabric 7 in any suitable way, herein typified by the rivet 13 75 and washer 14. The socket-carrying plate 11 is preferably constructed as shown, and preferably attached to the goods as shown in such a way that the casing 6 may be free to rotate thereon.

Referring now to the specific form of socket which I have elected to show in connection with the preferred embodiment of my invention, I have shown in Fig. 3 the socket 6 having a double notched aperture 17 90 therein and provided with a spring 18, the latter preferably arranged diagonally relative to the notched aperture.

If strain is exerted between the fabric carrying the stud and the fabric carrying the socket in such a direction as to bring the neck of the stud substantially directly against an adjacent portion of the spring 18, the casing 6 will turn on its carrying part in one direction or the other so that the neck of the stud may engage directly in one of the notches. As described in my copending application above referred to, these notches are not of sufficient depth to prevent separation of stud and socket by a 105 simple tipping movement at an angle greater

than that which is likely to be produced by the resolution of forces arising from lateral strain.

It will be understood that I use the word "fabric" in its broader sense, not only to include woven materials, but any flexible carrying medium.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A socket for separable fasteners comprising, in combination, a casing having a notched stud-receiving aperture, a spring in said casing, a metallic securing device rotatably engaging said casing and means for

fastening said securing device to a carrying part while leaving said casing free to rotate relative thereto.

2. A socket for separable fasteners comprising, in combination, a plate having a non-circular stud-receiving aperture therein, said aperture extended at one side to provide a narrowed portion into which the neck of the stud may enter to provide a lock against separation arising from resolution of forces under lateral strains, a metallic securing device for securing said plate to its carrying fabric, said securing device permitting rotative movement of said plate relative to its carrying fabric, thereby to permit said plate to turn so that the narrowed portion may lie toward the direction of strain between stud and socket.

In testimony whereof I have signed my name to this specification.

FRED S. CARR.
